UNITED STATES PATENT OFFICE.

ROYAL P. FARIES, OF WICHITA, KANSAS.

CARBURETER FOR GAS AND GASOLINE ENGINES.

1,086,359.

Specification of Letters Patent. Patented Feb. 10, 1914.

Application filed June 13, 1912. Serial No. 703,428.

To all whom it may concern:

Be it known that I, ROYAL P. FARIES, a citizen of the United States, residing at Wichita, in the county of Sedgwick and State of Kansas, have invented certain new and useful Improvements in Carbureters for Gas and Gasolene Engines; and I do hereby declare the following to be a full, clear, and exact description of the invention, such as will enable others skilled in the art to which it appertains to make and use the same.

My device relates to improvements in carbureters for gas and gasolene engines, and has for its object to provide means by which either natural or artificial gas can be used and by which either can be cut off and gasolene turned on instantly or vice versa.

Another object is to provide means to the accomplishment of these facts which are cheap and durable and which can be applied to any gas or gasolene engine.

I attain these objects by the mechanism illustrated in the accompanying drawings, described in the specification and succinctly defined in the appended claim.

Figure 1 is a general view of my device. Fig. 2 a vertical sectional view thereof taken on the dotted line 6, Fig. 3 a view of the transverse section 17 (Fig. 2) looking from the bottom. Fig. 4 illustrates the gasolene conduit communicating with the valve chamber. Fig. 5 a plan view of the guides 15 and 16 for the valve stem 43.

Similar numerals designate similar parts throughout the several views.

Referring to the drawings, Fig. 1, is a perspective view of my device which is divided into three sections 1, 2 and 3. These sections are removably connected together by screw threads 23 and 24, and each section is provided with a hexagonal portion as at 3', 10 and 38 so that wrenches can be applied for the assembling thereof. Threads 41 are made in section 3 for the reception of a gas pipe which conducts the gas into the device. Sections 3 and 2 are provided with transverse bridges 15 and 16 which have holes 42 in which plays up and down a valve stem 43. Fixed on said stem is a circular valve 37, normally seated in section 2. This valve is limited in its upward movement by the member 15. In the lower end of section 2 is a partition 17 having a

series of holes 18 therein and integral therewith is a downwardly extending tube 19. Section 1 will be referred to hereinafter as a generator and has a threaded portion 44 to receive a member which conducts air into the generator, laterally extending therefrom is a tube 4, which is for making connection with the engine and an extension 2', internally threaded to receive a gasolene conducting pipe, and an extension 5 having an inner chamber 12 and a reduced threaded extension 34 on which is screwed a cap 7, leaving therebetween a chamber 35 which is filled with any suitable material for a packing. Through said extension and packing extends a rod 9 on the outer end of which is a thumb-knob 8. On the inner end of said rod there is a cone point, usually termed a needle valve, which is normally seated in a conduit 33, communicating with the valve seat 36. A valve 29, having integral therewith a tube 26 of a size to pass up inside of the tube 19, and on the lower side of said valve are three laterally extending guides 30 which insure the proper seating of the valve. A hole is made through the valve into the aforesaid tube and is threaded to receive a screw bolt 25, having an oval head 28 and a threaded portion 39 and said bolt has a reduced extension which is free to move up and down in the hole 31 and when in a normal position, the upper end is adjacent the upper valve stem 43. Said bolt is provided with a lock-nut 27. Around the tube 19 is placed a spiral spring 20, which bears against the member 17 and the valve 29 which insures the seating of the valve.

It is to be observed the bolt 25 can be set in any desired position to compensate for the wear of the upper valve stem 43 and to contact it at the desired moment either raised or turned down so that the lower valve is operated without contacting the upper valve stem as would be the case if gasolene was used and the gas valve was to remain out of operation.

Having described the construction and assembling of my device, I will now describe its operation generally.

When I desire to operate an engine with gasolene, the bolt 25 is turned down so that in its upward flight it will not impinge the valve stem 43, and the upward movement

2
of the valve 29 is limited by the tube 19. When the air forces the valve up, as when entering the generator, the gasoline flows through the conduit 33 and out at the valve seat as at 33 and commingling with the air is carried up into the generator and enters the engine through the tube 4.

When I desire to immediately change from the use of gasoline to the use of gas, 10 I close the needle valve 32, turn the bolt 25 up so that it nearly contacts the valve stem 43, and when the air is being received into the generator the said valve raises valve 37 up and admits the gas which mixes with 15 the admitted air in the generator and is carried into the engine through the tube 4.

It is obvious that with my device, I can use either gas or gasoline and make an instantaneous change which is of great benefit 20 in case of an emergency.

From the foregoing it will be observed that I have provided a compact and durable device, comprehending positively coöperating elements, but while the present embodiment of the invention is believed at this time to be preferable, still I do not desire to limit myself to the structural details defined, but reserve the right to effect such modifications and variations as may be comprehended within the scope of the protection 30 prayed.

What I claim is:—

In a device of the character described, a casing comprising a multiplicity of sections and threaded together, two of said sections inclosing a gas chamber, a valve in one section mounted upon a stem and adapted to play up and down in transversely disposed bridges integral with said sections, a transverse foraminous partition in one section, a tube extending downward therefrom, an air valve seated in the lower section, guiding stems on its lower side and a tube on its upper, integral therewith and telescoping the aforesaid tube and an adjustable bolt threaded in said valve tube so that it may be set in any desired position whereby it will contact the aforesaid valve stem on a slight movement, a nut to lock said bolt in a fixed position, a spiral spring 50 on the aforesaid tube to insure positive action of the valve, a gasoline conduit having its terminal in the seat of the air valve, and means for opening and closing said conduit.

In testimony whereof, I have signed this specification in the presence of two subscribing witnesses.

ROYAL P. FARIES.
